UNITED STATES PATENT OFFICE.

JOHN A. GARVER, OF BRYAN, OHIO.

IMPROVEMENT IN WHEELBARROWS.

Specification forming part of Letters Patent No. 149,737, dated April 14, 1874; application filed January 24, 1874.

To all whom it may concern:

Be it known that I, JOHN A. GARVER, of Bryan, in the county of Williams and State of Ohio, have invented a new and valuable Improvement in Wheelbarrows; and I do hereby declare that the following is a full, clear, and exact description of the construction and operation of the same, reference being had to the annexed drawings making a part of this specification, and to the letters and figures of reference marked thereon.

Figure 1 of the drawings is a representation of a side view of my wheelbarrow. Fig. 2 is a plan view of the same.

This invention has relation to wheelbarrows for moving heavy loads, wherein the parts composing the barrows require to be made very strong, and to be substantially braced. It consists, mainly, in the use of curved braces or brackets and curved legs, which are halved together and united so as to brace the legs and rails and afford retaining extensions for the tray, as will be hereinafter explained.

In the annexed drawings, A designates the receiver or tray, and B the bars or rails on which the tray is rigidly secured by means of bolts. The rear extensions of the rails B form the handles B¹ of the barrow, and the front extensions form the wheel-arms B². C C designates the legs, and D D the braces for these legs. E represents the wheel, which, with the hub g, I shall cast entire. A bolt or axle, a, passes loosely through the hub g and through the ends of the arms B², and receives nuts b b'

on its ends. The nuts b' b' inside of the arms, and the outside nuts b b', secure the bolt a rigidly. Secure this bolt in place and tie together the arms, so that they will not spread under the roughest usage. The braces D and legs C are arcs of circles, and they are halved together, and also halved to the rails B, and firmly secured by bolts. The upper ends d and e of these legs and braces extend above the rails B, and are properly beveled to receive the tray A and afford supports for its front and rear sides of this tray. G represents a cross-piece, which is bolted to the under sides of the rails B, near the front attachments of the braces D, for the purpose of sustaining these rails against spreading. A bar, C', is also secured to the lower ends of the legs C to prevent them from spreading and to sustain them against lateral strain.

What I claim as new, and desire to secure by Letters Patent, is—

The curved braces D and legs C, combined with the rails B, and having beveled extensions a and e above the rails for receiving, holding, and supporting the tray A, substantially as described.

In testimony that I claim the above I have hereunto subscribed my name in the presence of two witnesses.

JOHN A. GARVER.
